FRONT PANEL SECTION FOR A SPEAKER ENCLOSURE OR SIMILAR ARTICLE

Harry B. Shaper, East Hills, Long Island, N.Y., assignor
to Dyna-Empire, Inc., Garden City, Long Island, N.Y.,
a corporation of New York

Filed Dec. 15, 1964, Ser. No. 83,230

Term of patent 14 years

(Cl. D26—14)

FIG. 1 is a front elevational view of a front panel section for a speaker enclosure or similar article, showing my new design;

FIG. 2 is a right side elevational view of the same panel section, the left side view being substantially a mirror image thereof;

FIG. 3 is a top plan view of the same panel section, the bottom plan view being substantially a mirror image thereof;

FIG. 4 is a cross-sectional view along line 4-4 of FIG. 1;

FIG. 5 is a cross-sectional view along line 5-5 of FIG. 1;

FIG. 6 is a front elevational view of a front panel section for a speaker enclosure or similar article, showing a modification of my new design;

FIG. 7 is a right side elevational view of the panel section shown in FIG. 6, the left side view being substantially a mirror image thereof;

FIG. 8 is a top plan view of the panel section shown in FIG. 6, the bottom plan view being substantially a mirror image thereof;

FIG. 9 is a cross-sectional view along line 9-9 of FIG. 6; and

FIG. 10 is a cross-sectional view along line 10-10 of FIG. 6.

In the design shown in FIGS. 6 to 10 the beveled side surfaces do not have the array of adjacent longitudinally extending grooves which are embodied in the beveled side surface of the design shown in FIGS. 1 to 5.

This application is a continuation-in-part of my two copending applications, Serial Nos. D. 77,073 and D. 77,083, both filed October 21, 1963, and abandoned subsequent to filing this application.

I claim:

The ornamental design for a front panel section for a speaker enclosure or similar article, as shown and described.
